CONTROL

Edward P. Bullard, III, Fairfield, Conn., assignor
to The Bullard Company, a corporation of
Connecticut

Application September 7, 1946, Serial No. 695,533

3 Claims. (Cl. 175—335)

1

This invention relates to machine tools, and particularly to a manually-operated control for effecting selected speed-changes of a rotating part in a machine tool.

Objects of the invention include the provision of a manually-operated control for a rotatable part of a machine tool, freely suspended in space and easily accessible to an operator; the provision of such a control in which as many as twenty speed changes can be effected by turning a single rotatable lever through 360°; the provision of such a control in which numerous solenoids are adapted to be energized in different groups of pre-determined solenoids each to effect a greater number of speed changes in a transmission than there are solenoids for effecting such changes; the provision of a pendant control for the headstock of a machine tool; the provision of such a pendant control in which a single, rotatable shaft within the pendant includes as many cams thereon as there are solenoids to be operated, and so arranged that the cams cooperate to close combinations of switches to energize the solenoids in groups of pre-determined solenoids each; the provision of such a pendant control for operating headstock gear-shifting solenoids in which a rotatable member for selectively actuating a plurality of switches is combined with a single switch actuator for a solenoid adapted to effect operation of a headstock clutch and brake; and the provision of an interlock between the rotatable switch actuating member and the single switch actuator so that the former cannot be rotated when the latter is in a pre-determined position.

The above, as well as other objects and novel features of the invention, will become apparent from the following specification and accompanying drawing, in which:

Figure 1 is a front elevational view of a vertical turret lathe to which the principles of the invention have been applied; and

Fig. 2 is a schematic wiring diagram of an electrical circuit employed in the practice of the invention.

Referring to Fig. 1 the invention is shown as applied to a vertical turret lathe including a base 30 in which the spindle of a work-supporting table 31 is journaled. A standard 32 extends vertically behind the table 31 from the base 30 and includes vertical ways 33, 34 along which a cross rail 35 is adapted to be reciprocated in a vertical plane. A saddle 36 is mounted on the cross rail 35 and is adapted to be moved horizontally therealong by the action of a screw 37 that is caused to be rotated in both directions by

a feedworks transmission 38. A slide 39 is mounted on the saddle 36 for vertical motion through the action of a splined shaft 40 that is also driven through the transmission 38. A turret 41 for supporting tools is mounted on the slide 39, and from the foregoing it is evident that tools mounted thereon can be moved relatively to work mounted for rotation on table 31.

A better understanding of the details so far described can be obtained from Patent 2,384,809 granted in the name of E. P. Bullard, III, et al. The feedworks 38 is driven from a headstock transmission that rotates table 31, and which is shown and described in the above-identified patent. The headstock transmission of said patent includes sliding change-speed gears that are adapted to produce twenty different rates of rotation of the table 31 upon the selective actuation of nine hydraulic control valves that are operated by a rotatable drum as clearly disclosed in said patent. A tenth valve described in said patent controls the operation of a clutch and brake for the headstock. In the present invention, ten valves similar to those in said patent are adapted selectively to be operated by ten solenoids, A, B, C, D, E, F, G, H, I and J, for setting up twenty different rates of rotation of the work-supporting table 31 and for operating a clutch and brake therefor.

Referring to Fig. 2, solenoids A to I inclusive provide the gear changes in the headstock transmission for table 31, while solenoid J effects operation of the clutch and brake for said transmission. The solenoids A to J inclusive may be located at any convenient point of the machine tool, but preferably are positioned within a housing containing the hydraulic control valves which they are adapted to operate. Selective energization of the solenoids A to J is effected, in accordance with the principles of the present invention, by operating a control at a point in close proximity to the work table 31 so that the operator has free access thereto as well as to the work on table 31. The control device for operating solenoids A to J is in the form of a freely suspended pendant or housing 42 of box-like construction attached to the end of a flexible conduit 43 that extends upwardly through a hollow tube 44 pivotally attached to the top of the standard 32.

The box-like pendant 42 is adapted to support make-and-break switches A' to J', one for each of the solenoids A to J. It also supports shaft 45 having cams 46 to 54 thereon for closing switches A' to I' in accordance with a predetermined order so that twenty different groups

of pre-determined of said solenoids are energized upon a single revolution of shaft 45. A disc 55 is fixed to the one end of shaft 45 and, accordingly, rotates with it. A series of stationary indices numbered 1 to 20 encircle the disc 55 and represent the twenty combinations of solenoids desired to be energized to produce the twenty rates of rotation of the table 31. The disc 55 includes a pointer 56 and a handle 57 for indicating the combination of solenoids energized and to manually rotate the shaft 45, respectively. One combination of groups of solenoids A to I for producing twenty different combinations is as follows: A, C, F; A, C, G; A, C, H; A, C, I; A, D, F; A, D, G; A, D, H; A, D, I; B, C, F; B, C, G; B, C, H; B, C, I; B, D, F; B, D, G; B, D, H; B, D, I; E, F; E, G; E, H; E, I. From the foregoing, it is evident that solenoid A is energized in the first eight combinations. Accordingly, cam 46 on shaft 45 is provided with an effective portion 58 adapted to close switch A' during the first eight positions of the pointer 56, namely, from position 1 to position 8. The first four combinations require solenoid C to be energized. Accordingly, the cam 50 is provided with an effective portion 59 that maintains switch C' closed during the first four positions of pointer 56. These first four combinations also require solenoids F, G, H and I to be energized successively. Accordingly, cams 41, 49, 51 and 53 are provided with effective portions 60, 61, 62 and 63 that successively close switches F', G', H' and I' during the first four positions of pointer 56.

The second four combinations require solenoid D to be energized. Accordingly, cam 52 is provided with an effective portion 64 that maintains switch D' closed during the second four movements of indicator 56, namely, from position 5 to position 8. The second four combinations also require the successive re-energization of solenoids F, G, H and I. Accordingly, cams 47, 49, 51 and 53 are provided with effective portions 65, 66, 67 and 68 that successively close switches F', G', H' and I' when indicator 56 is at positions 5, 6, 7 and 8, respectively. The combinations represented by positions 9 to 16 of the index 56 require the energization of solenoid B. Accordingly, cam 48 is provided with an effective portion 69 that maintains switch B' closed when index 56 is at any of positions 9 to 16. The third four combinations also require solenoid C to be energized. Accordingly, cam 50 is provided with a second effective portion 70 that maintains switch C' closed when index 56 is at positions 9, 10, 11 and 12. Additionally, the third four combinations require the successive energization of solenoids F, G, H and I, and for this reason cams 47, 49, 51 and 53 include additional effective points 71, 72, 73 and 74 that successively close switches F', G', H' and I' when index 56 is respectively at positions 9, 10, 11 and 12.

The fourth four combinations represented by positions 13, 14, 15 and 16 of the index 56 not only require solenoid B to be energized but also solenoid D. Therefore, cam 52 includes a second effective portion 75 that maintains switch D' closed when index 56 is in positions 13, 14, 15 and 16. Additionally, these four combinations require the successive energization of solenoids F, G, H and I. For this reason, cams 47, 49, 51 and 53 include additional effective portions 76, 77, 78 and 79 that successively close switches F', G', H' and I' when index 56 is successively in positions 13, 14, 15 and 16.

The last four combinations require solenoid E

to be energized. Accordingly, cam 54 is provided with an effective portion 80 that maintains switch E' closed when index 56 is in positions 17, 18, 19 and 20. Finally, the last four combinations require the successive energization of solenoids F, G, H and I, and cams 47, 49, 51 and 53 are provided with points 81, 82, 83 and 84 that successively close switches F', G', H' and I' when index 56 is successively in positions 17, 18, 19 and 20.

When the pendant control is employed to energize solenoids that control the speed changes of a work-supporting spindle, as is the present case, a clutch and brake must be operated between each change of speed in order to disengage the headstock transmission from the work-supporting spindle prior to making a change, and to re-engage said headstock and spindle after a new rate of speed has been initiated. The solenoid J is employed to operate a hydraulic valve similar to the one employed in the above-referred-to patent that controls the action of the clutch and brake in that case. The switch J' is adapted manually to be closed by a toggle switch lever 85 including a cam disc 86 that cooperates with the switch J'. It is important, however, that the shaft 45 be interlocked with the switch J' so that a different speed rate is not initiated when the headstock is clutched to the work-supporting table 31. Accordingly, a ratchet 87 is fixed to shaft 45 and includes twenty teeth adapted to cooperate with a detent 88 that is spring-urged into engagement with said teeth. A draw bar 89 is attached to the cam 86 and is adapted to reciprocate upon operation of switch lever 85 such that it permits detent 88 to descend when switch J' is open, but prevents such action when switch J' is closed. From the foregoing it is evident that shaft 45 can be rotated only when switch J' is closed and hence work table 31 de-clutched from the headstock transmission.

Although the various features of the improved control mechanism have been shown and described in detail to fully disclose one embodiment of the invention, it will be evident that numerous changes may be made in such details, and certain features can be used without others, without departing from the principles of the invention.

What is claimed is:

1. In a machine tool, nine solenoids adapted to be energized in different combinations of pre-determined solenoids each to provide twenty different combinations; nine switches, one for each of said solenoids; a cam shaft adapted to be moved to twenty different angular positions in one revolution; four cams on said cam shaft, each having five effective portions so arranged that four of said switches are closed in succession five times during the movement of said cam shaft to its twenty positions; two cams on said cam shaft having effective portions for respectively maintaining two of said switches closed during the first and second eight positions to which said cam shaft can be moved; two additional cams on said cam shaft, each having effective portions for maintaining two of said switches closed alternately during the first, second, third and fourth four positions to which said cam shaft is adapted to be moved; and a single cam on said cam shaft having an effective portion for maintaining one of said switches closed during the last four positions to which said cam shaft is adapted to be moved.
2. In a machine tool, a plurality of solenoids for controlling the rate of rotation of a rotatable

member within said machine tool; a housing adjacent the rotatable member of said machine tool; a plurality of switches within said housing, one for each of said solenoids; a cam shaft within said housing including cams for closing all except one of said switches; a handle for rotating said cam shaft; means for manually operating the switch not affected by said cam shaft; and means between said manually-operable means and said cam shaft for preventing the latter's rotation except when said manually-operable means is in a pre-determined position.

3. In a machine tool, a plurality of solenoids adapted to be energized in certain groups to provide more combinations than there are solenoids; a housing in close proximity to said machine tool so as to be freely accessible to an operator; a plurality of switches in said housing, one for each of said solenoids; a cam shaft within said housing, adapted to be moved to as many angular positions in one revolution thereof as there are desired combinations of solenoids to be energized; a plurality of cams on said cam shaft, each having effective portions so arranged that all except one of said switches are closed in accordance 25

with a pre-determined order during the movement of said cam shaft through one revolution; a manually-operable lever on said housing for operating the switch not affected by said cam shaft; and means between said lever and said cam shaft to prevent the latter's rotation when said lever is in a pre-determined position.
